UNITED STATES PATENT OFFICE

LLOYD M. KEIGHLEY, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed November 10, 1926. Serial No. 147,551.

This invention relates to cooling units for mechanical refrigerators, and more particularly to cooling units which are adapted to be installed in refrigerating cabinets of the household type. However, it is to be understood that the present invention may be adapted for larger refrigerating cabinets of the commercial type.

The present invention includes among its objects the provision of a cooling unit of simple and economical construction, which will quickly congeal or freeze substances which are placed within a freezing compartment provided by the unit, and which will effectively cool the food compartment of the cabinet.

Further objects and advantages of the present invention will be apparent from the following description, reference being had to the accompanying drawings, wherein a preferred form of the present invention is clearly shown.

In the drawings:

Fig. 1 is a front view of a refrigerator cabinet with the doors open in order to show the food compartment and a cooling unit within a cooling compartment;

Fig. 2 is a view on a larger scale than Fig. 1, showing the front view of the cooling unit which is suspended within the cooling compartment of a cabinet, the walls of which are shown in vertical section;

Fig. 3 is a side elevation of the cooling unit drawn to the same scale as Fig. 2; and

Fig. 4 is a front view of a modified form of cooling unit.

Referring to the drawings, 20 designates a refrigerator cabinet which provides an L-shaped food compartment 21 separated from a cooling compartment 22 by a horizontal partition 23 and a vertical partition 24. The partition 24 is provided with a flue 25, admitting relatively warm air from the food compartment 21 to the cooling compartment 22; and the partition 23 is provided with a flue 26, admitting cooled air from the compartment 22 to the compartment 21. The partition 23 supports a baffle 27 which prevents moisture, dripping from the cooling unit above, from entering the flue 26. The

baffle 27 directs such moisture upon the upper surface of the partition 23, and this moisture is conducted away through a drain pipe 28.

The cooling unit located within the cooling compartment 22, includes a boiler or header 30 attached to the top wall of the cabinet by bracket members 31 and 32. Condensed refrigerant is conducted to the header 30 from a compressor and condenser (not shown) through a pipe 33 and a fitting 34. Refrigerant is admitted from the fitting 34, as needed, by a float-controlled valve (not shown), of suitable construction, located within the header 30. Expanded refrigerant is conducted back to the compressor through a fitting 35 and a pipe 36. The refrigerating compressor and condenser with which the pipes 33 and 36 are connected, may be located outside of the cabinet, if desired, or may be placed within a machine compartment located below the food compartment 21, said compartment having a removable front wall 37 provided with louvers 38.

Referring to Figs. 1, 2 and 3, the header 30 is connected with depending loops 40, 75 of metal of good thermal conductivity, arranged in horizontal rows on each side of a freezing space 41 below the header. Each loop includes a straight duct 42 and a duct 43 comprising a plurality of superposed serpentine loops providing a relatively large heat-absorbing surface. The ducts 43 cooperate with the header to enclose the space 41 and to isolate it from air currents passing adjacent the unit. The space is adapted to receive one or more metal shelves or sleeves 44 which are attached to and thermally connected with the serpentine ducts 43. The sleeves 44 receive trays 45 for containing matter to be frozen.

By virtue of the present construction, the cooling unit provides what may be termed a freezing zone for quickly freezing or congealing substance and provides what may be termed a cooling zone which maintains the refrigerator at the desired temperature, not too cold for general refrigeration. The freezing zone, provided by the ducts 43, is nested within the outwardly lying cooling zone and thereby protected from the warming effects 100

of the circulating air or medium which flows over the unit.

- Preferably, the loops 40 are connected with the header 30 before the sleeves are attached to the ducts 43. The construction and arrangement of the loops permit bending the loops transversely of the header so that the ducts 43 may be adjusted to fit snugly against the sides of the sleeves 44.
- 10 The serpentine bends in the ducts 43 are so connected with the sleeves as to provide a relatively great area of thermal contact to obtain the quick freezing of the contents of the trays. The ducts 43 also provide walls of relatively great area which shield the sleeves from currents of warmer air. In operation, frost will collect at a relatively rapid rate upon the ducts 43 and thus provide an ice wall further isolating and insulating the freezing space. Thus the unit is operative to provide for rapid freezing while effectively cooling air which circulates adjacent the ducts 42. Even under conditions causing the ducts 42 to defrost substantially during the idle periods of the refrigerating apparatus, some frost will remain upon the coils 43, owing to the relatively great area of these coils which is exposed to frosting.

In the form of invention shown in Fig. 30 4, the ducts 42 and 43 are parts of loops 40a which encircle the freezing space 41. The bottom portions or yokes of the loops 40a provide additional heat-absorbing surface; and those portions of these yoke portions below the bottom sleeve 44 will become frosted and thereby serve further to isolate the freezing space 41.

While the form of embodiment of the invention as herein disclosed, constitutes a preferred form, it is to be understood that other forms might be adopted, all coming within the scope of the claims which follow.

What is claimed is as follows:

1. A cooling unit for mechanical refrigerators comprising, an elongated header, and a plurality of ducts depending from the header, portions of said ducts being adapted to provide tortuous passages and providing walls of relatively great area which cooperate to provide a freezing zone, said portions comprising serpentine-looped duct members facing flatwise the freezing space, said ducts including portions substantially entirely exposed to air circulating adjacent the cooling unit.

2. A cooling unit for mechanical refrigerators comprising, an elongated header, and a plurality of ducts depending from the header, portions of said ducts being adapted to provide tortuous passages and providing walls of relatively great area which cooperate to provide a freezing zone, said portions being each provided with superposed, 60 serpentine bends, said ducts including por-

tions substantially entirely exposed to air circulating adjacent the cooling unit.

3. A cooling unit for mechanical refrigerators adapted to be placed in the path of medium to be cooled thereby, said cooling unit comprising conduit means having portions spaced from one another to provide a freezing zone therebetween, one of said conduit means comprising a loop having a vertically extending tortuous branch facing the freezing zone flatwise, and having another branch lying outwardly of the freezing zone in the path of the circulating medium.

4. A cooling unit for mechanical refrigerators adapted to be placed in the path of the medium to be cooled thereby, said cooling unit comprising heat exchange means having a portion constructed and arranged to provide a freezing zone, and another portion formed to provide a cooling zone, the material of said second mentioned portion being spaced from the first portion and lying in the path of the circulating medium and so constructed and arranged as to provide a shield of heat exchange material for shielding the freezing zone from the action of the circulating medium; one of said portions including duct means having a tortuous portion lying parallel with the freezing zone.

5. A cooling unit for mechanical refrigerators adapted to be placed in the path of medium to be cooled thereby, said cooling unit comprising opposed duct loops having tortuous branches cooperating to provide a freezing zone and other branches extending outwardly of the freezing zone in the path of the circulating medium and so constructed and arranged as to provide a shield of heat exchange material for shielding the freezing zone from the action of the circulating medium.

6. A cooling unit for mechanical refrigerators adapted to be placed in the path of medium to be cooled thereby, said cooling unit comprising duct loops, certain branches of said loops being tortuous, certain branches cooperating to provide a freezing zone lying longitudinally of the tortuous portions, and certain other branches lying outwardly of the freezing zone in the path of the circulating medium and so constructed and arranged as to provide a shield of heat exchange material for shielding the freezing zone from the action of the circulating medium.

7. A cooling unit for mechanical refrigerators adapted to be placed in the path of medium to be cooled thereby, said cooling unit comprising duct loops, certain branches of said loops being arranged in spaced rows and cooperate to provide a freezing zone, said branches including tortuous portions lying substantially in the plane of said rows, and certain other branches lying outwardly of the freezing zone in the path of the circulating medium and so constructed and arranged

as to provide a shield of heat exchange material for shielding the freezing zone from the action of the circulating medium.

8. A cooling unit for mechanical refrigerators adapted to be placed in the path of medium to be cooled thereby, said cooling unit comprising opposed duct loops, certain branches of said loops being tortuous, certain branches cooperating to provide a freezing zone between the opposed duct loops, and certain other branches lying outwardly of the freezing zone in the path of the circulating medium and so constructed and arranged as to provide a shield of heat exchange material for shielding the freezing zone from the action of the circulating medium.

9. A cooling unit for mechanical refrigerators adapted to be placed in the path of medium to be cooled thereby, said cooling unit comprising opposed duct loops, certain branches of said loops being tortuous and cooperating to provide a freezing zone between the opposed duct loops, and certain other branches lying outwardly of the freezing zone in the path of the circulating medium and so constructed and arranged as to provide a shield of heat exchange material for shielding the freezing zone from the action of the circulating medium.

10. A cooling unit for mechanical refrigerators comprising a plurality of conduits arranged in spaced relation to form rows of ducts, the ducts of a row including tortuous portions lying substantially in the plane of the row, said rows of ducts cooperating to provide a freezing zone therebetween adapted to receive a horizontally elongated ice tray.

11. A cooling unit for mechanical refrigerators comprising a plurality of tortuous conduits arranged in spaced relation to form rows of ducts, the tortuous portions of the ducts lying substantially in the planes of the rows and cooperating to provide a freezing zone therebetween adapted to receive a horizontally elongated ice tray.

12. A cooling unit adapted to be placed in the path of cooling medium for cooling such medium, said cooling unit comprising a plurality of conduits arranged in spaced relation to form rows of ducts, the ducts of a row including tortuous portions lying substantially in the plane of the row, said rows of ducts cooperating to provide a freezing zone therebetween, and heat exchange means in intimate thermal contact with a refrigerant, the material of said heat exchange means lying outwardly of the freezing zone and arranged to provide a shield of heat exchange material for shielding the freezing zone from the action of the circulating medium.

In testimony whereof I hereto affix my signature.

LLOYD M. KEIGHLEY.
